(57) **ABSTRACT**

A disappear-on-demand material actuator, including a trigger disposed in operable contact with the material, the trigger configured to respond to manipulation of a tubing string in operable communication with the actuator, and an electrical energy source electrically connected to the material and configured to supply electrical energy to the material upon a sequence initiation of the trigger. A method for actuating a disappear-on-demand material, including manipulating a tubing string, changing a trigger on the actuator, and conveying electrical energy to the material.

FIG. 1A

FIG. 2

FIG. 2A

FIG. 3

FIG. 4

FIG. 5

FIG. 6

FIG. 8

10

FIG. 9

10

FIG. 10

material 36, thereby igniting the same and causing it to disappear leaving only a small amount of ash 38 in its place. The DoD material disappearing can be used as an actuation event in several ways. The material could prior to igniting simply be a physical impediment to something else moving, or could be a structural member restraining something like collet fingers, etc.

In another embodiment, referring to FIGS. 7-9, the turbine 26 is replaced with a biser 40. The biser 40 is employed in a condition to store potential energy. The energy may be input from the factory build of the actuator 10 or may be “wound” or otherwise input at the time of deployment. In either case, the potential energy of the biser 40, which may be a compression spring, a tension spring, a torsion spring, etc., is used to spin the generator 28. Release of the potential energy of the biser 40 is effected by manipulation of the string 12c as in the forgoing embodiment and simply moves a catch 42 so the biser 40 may release the stored energy to become kinetic energy to spin the generator 28. As illustrated, there may be two shafts 44 and 46 with gearing 48 and 50 thereon to step up or step down the spin ratio created by the biser 40. In other respects the generator 28 is similar to the foregoing embodiments. The switch 34 and DoD Material 36 are also similar.

A method for actuating a DOD material actuator is disclosed wherein intervention is avoided. Specifically, intervention means to run another string into the well in order to take an action somewhere inside the well. Causing actuation without an intervention is a time and cost saver and can be effected in accordance with the teachings herein by employing string manipulation to trigger the actuator 10

Referring to FIG. 10, a borehole system 60 is illustrated. The system 60 comprises a borehole 62 in a subsurface formation 64. A string 66 is disposed within the borehole 62. A DOD material actuator 10 as disclosed herein is disposed within or as a part of the string 66.

Set forth below are some embodiments of the foregoing disclosure:

Embodiment 1: A disappear-on-demand material actuator, including a trigger disposed in operable contact with the material, the trigger configured to respond to manipulation of a tubing string in operable communication with the actuator, and an electrical energy source electrically connected to the material and configured to supply electrical energy to the material upon a sequence initiation of the trigger.

Embodiment 2: The actuator as in any prior embodiment, wherein the trigger is a sliding sleeve.

Embodiment 3: The actuator as in any prior embodiment, wherein the trigger is a switch.

Embodiment 4: The actuator as in any prior embodiment, wherein the trigger is a controller.

Embodiment 5: The actuator as in any prior embodiment, wherein the electrical energy source is a battery.

Embodiment 6: The actuator as in any prior embodiment, wherein the electrical energy source is a generator.

Embodiment 7: The actuator as in any prior embodiment, wherein the generator includes magnets and coils.

Embodiment 8: The actuator as in any prior embodiment, wherein the actuator includes a drive operably connected to the generator.

Embodiment 9: The actuator as in any prior embodiment, wherein the drive is a turbine.

Embodiment 10: The actuator as in any prior embodiment, wherein the drive is a biser.

Embodiment 11: The actuator as in any prior embodiment, wherein the biser is a compression spring.

Embodiment 12: The actuator as in any prior embodiment, wherein the biser is a torsion spring.

Embodiment 13: The actuator as in any prior embodiment, further including a voltage control switch.

Embodiment 14: The actuator as in any prior embodiment, wherein the voltage control switch measures a signal and upon reaching a threshold for the signal, facilitates passage of electrical energy to the material.

Embodiment 15: A method for actuating a disappear-on-demand material, including manipulating a tubing string, changing a trigger on the actuator as in any prior embodiment, and conveying electrical energy to the material.

Embodiment 16: The method as in any prior embodiment, wherein the changing includes sliding a sliding sleeve.

Embodiment 17: The method as in any prior embodiment, wherein the conveying electrical energy is from a battery.

Embodiment 18: The method as in any prior embodiment, further comprising generating electrical energy.

Embodiment 19: The method as in any prior embodiment, wherein the generating includes relatively moving coils and magnets to generate a current.

Embodiment 20: The method as in any prior embodiment, wherein the generating includes flowing of fluid through a turbine to drive a generator of the electrical energy.

Embodiment 21: The method as in any prior embodiment, wherein the flowing includes diverting a flow from a string with which the actuator is operably associated through the turbine.

Embodiment 22: The method as in any prior embodiment, wherein the generating includes releasing potential energy in a biser to become kinetic energy used to generate the electrical energy.

The use of the terms “a” and “an” and “the” and similar referents in the context of describing the invention (especially in the context of the following claims) are to be construed to cover both the singular and the plural, unless otherwise indicated herein or clearly contradicted by context. Further, it should be noted that the terms “first,” “second,” and the like herein do not denote any order, quantity, or importance, but rather are used to distinguish one element from another. The terms “about,” “substantially” and “generally” are intended to include the degree of error associated with measurement of the particular quantity based upon the equipment available at the time of filing the application. For example, “about” and/or “substantially” and/or “generally” can include a range of +8% of a given value.

The teachings of the present disclosure may be used in a variety of well operations. These operations may involve using one or more treatment agents to treat a formation, the fluids resident in a formation, a borehole, and/or equipment in the borehole, such as production tubing. The treatment agents may be in the form of liquids, gases, solids, semi-solids, and mixtures thereof. Illustrative treatment agents include, but are not limited to, fracturing fluids, acids, steam, water, brine, anti-corrosion agents, cement, permeability modifiers, drilling muds, emulsifiers, demulsifiers, tracers, flow improvers etc. Illustrative well operations include, but are not limited to, hydraulic fracturing, stimulation, tracer injection, cleaning, acidizing, steam injection, water flooding, cementing, etc.

While the invention has been described with reference to an exemplary embodiment or embodiments, it will be understood by those skilled in the art that various changes may be made and equivalents may be substituted for elements thereof without departing from the scope of the invention. In addition, many modifications may be made to adapt a

particular situation or material to the teachings of the invention without departing from the essential scope thereof. Therefore, it is intended that the invention not be limited to the particular embodiment disclosed as the best mode contemplated for carrying out this invention, but that the invention will include all embodiments falling within the scope of the claims. Also, in the drawings and the description, there have been disclosed exemplary embodiments of the invention and, although specific terms may have been employed, they are unless otherwise stated used in a generic and descriptive sense only and not for purposes of limitation, the scope of the invention therefore not being so limited.

What is claimed is:

1. A disappear-on-demand material actuator, comprising:
a housing defining a chamber, the housing including a port fluidly communicating the chamber to an inside diameter of the housing and a one-way check valve fluidly communicating the chamber and the inside diameter of the housing the one-way check valve allowing fluid to flow in only one direction from the chamber to the inside diameter of the housing;
a configuration disposed radially inwardly of the housing that reduces flow in the inside diameter of the housing between the port and the one-way valve;
a trigger disposed adjacent the port, the trigger operable to open the port or block the port,
and
an electrical energy source disposed in the chamber, the source electrically connected to the material and configured to supply electrical energy to the material upon flowing of fluid through the chamber.
2. The actuator as claimed in claim 1, wherein the trigger is a sliding sleeve.
3. The actuator as claimed in claim 1, wherein the trigger is a switch.
4. The actuator as claimed in claim 1, wherein the trigger is a controller.
5. The actuator as claimed in claim 1, wherein the electrical energy source is a battery.
6. The actuator as claimed in claim 1, wherein the electrical energy source is a generator.
7. The actuator as claimed in claim 6, wherein the generator includes magnets and coils.
8. The actuator as claimed in claim 6, wherein the actuator includes a drive operably connected to the generator.
9. The actuator as claimed in claim 8, wherein the drive is a turbine.
10. The actuator as claimed in claim 8, wherein the drive is a biaser.

11. The actuator as claimed in claim 10, wherein the biaser is a compression spring.
12. The actuator as claimed in claim 10, wherein the biaser is a torsion spring.
13. The actuator as claimed in claim 1, further including a voltage control switch.
14. The actuator as claimed in claim 13, wherein the voltage control switch measures a signal and upon reaching a threshold for the signal, facilitates passage of electrical energy to the material.
15. A method for actuating a disappear-on-demand material, comprising:
manipulating a tubing string;
changing a trigger on the actuator as claimed in claim 1;
and
conveying electrical energy to the material.
16. The method as claimed in claim 15, wherein the changing includes sliding a sliding sleeve.
17. The method as claimed in claim 15, wherein the conveying electrical energy is from a battery.
20. The method as claimed in claim 15, further comprising generating electrical energy.
18. The method as claimed in claim 18, wherein the generating includes relatively moving coils and magnets to generate a current.
25. The method as claimed in claim 18, wherein the generating includes flowing of fluid through a turbine to drive a generator of the electrical energy.
21. The method as claimed in claim 20, wherein the flowing includes diverting a flow from a string with which the actuator is operably associated through the turbine.
22. The method as claimed in claim 18, wherein the generating includes releasing potential energy in a biaser to become kinetic energy used to generate the electrical energy.
23. A disappear-on-demand material actuator, comprising:
a housing defining a chamber;
a trigger disposed in the housing such that the trigger may be manipulated from within an inside diameter of the housing, the trigger including a catch;
a drive biased with potential energy and prevented from moving by the catch and movable following movement of the catch out of engagement therewith, the drive including a plurality of gears having a gear up or gear down ratio;
an electrical energy source disposed in the chamber, the source electrically connected to the material and configured to supply electrical energy to the material upon movement of the drive to initiate a disappear on demand reaction.
